The ornamental design for the two-part golf tee, as shown and described.

DESCRIPTION

FIG. 1 is an isometric view of the golf tee showing my new design in a raised position;

FIG. 2 is an isometric view showing the design in a lowered position;

FIG. 3 is an exploded isometric view thereof;

FIG. 4 is an elevational view of the base component shown separated from the stem component for clarity;

FIG. 5 is a cross sectional view along line 5-5 of FIG. 4;

FIG. 6 is an enlarged fragmentary view of the portion of FIG. 5 indicated by circle 6;

FIG. 7 is an isometric view of the stem component of the design shown separated from the base component for clarity;

FIG. 8 is an enlarged fragmentary view of the portion of FIG. 7 indicated by circle 8;

FIG. 9 is an isometric view showing the base component in cross section along 9-9 of FIG. 1, and the stem component in a raised position; and,

FIG. 10 is an isometric view showing the base component in cross section along line 10-10 of FIG. 1, and the stem component in a lowered position.

The appearance within the unshaded circular area showing within the top end in FIGS. 1, 3, 7, 9 & 10 forms no part of the claimed design.
